UNITED STATES PATENT OFFICE.

CHARLES L. DEPOLIER, OF NEW YORK, N. Y.

WATCHCASE, &c.

1,139,107.

Specification of Letters Patent.

Patented May 11, 1915.

Application filed January 9, 1915. Serial No. 1,280.

To all whom it may concern:

Be it known that I, CHARLES L. DEPOLIER, a citizen of the United States, residing in the borough of Brooklyn of the city of 5 New York, in the county of Kings, in the State of New York, have invented certain new and useful Improvements in Watch-cases, &c., of which the following is a specification, reference being had to the accompanying drawing, forming a part hereof.

Small watches, designed for use as bracelet watches, are often worn as sautoir watches and as chatelaine brooch watches, but wrist watches must be provided, at a 15 point opposite the bow, with some means of attachment for the bracelet, and as bracelet watches have been made hitherto such means of attachment are permanently fixed outside of the watch case so that it becomes apparent at once that the wearer is using a bracelet watch as a chatelaine or sautoir watch. The result is that many persons refuse to wear what is known as a convertible watch, that is, a watch which can be used either as 20 25 a bracelet watch or as a chatelaine or sautoir watch.

The object of this invention is to provide for a watch case a means of attachment, opposite the bow, for the bracelet, which instead of being permanently fixed on the outside of the case may be made to disappear or at least to become not readily discernible and in accordance with the invention the watch case or brooch, or whatever similar 30 35 article is to be worn like a watch, is provided with a seat or opening in which is seated movably an attaching device by means of which connection with the bracelet or chain may be effected. It will be obvious 40 45 that such disappearing device can be made in many different ways.

In the accompanying drawings are therefore illustrated several different forms in which the invention may be embodied and 45 in the drawings—

Figure 1 is a view in perspective showing a bracelet watch provided with one form of the improved attaching device together with a bracelet which has one end connected to 50 the watch bow and the other to the attaching device. Fig. 2 is a view showing such a watch as that shown in Fig. 1 attached by the bow to a chain, as a sautoir watch, with the opposite attaching device concealed. 55 Fig. 3 is a partial front view of a watch case

equipped with one form of the attaching device. Fig. 4 is an edge view of the watch case shown in Fig. 3 with the attaching device seated in its concealing recess. Fig. 5 is an edge view of the watch case, seen from 60 a point of view at right angles to that of Fig. 4, with the attaching device open. Fig. 6 is a view similar to Fig. 4 but showing a slight modification. Figs. 7, 8 and 9 are views illustrating another embodiment of 65 the invention in which the attaching eye is swiveled to the watch case center. Figs. 10 and 11 are views showing still another embodiment of the invention, in which the attaching eye is pivoted and moved through a 70 slot in the watch case center. Fig. 12 is a view showing still another modification in which the attaching eye is supported by a spring. Fig. 13 shows another embodiment 75 of the invention in which a ball is used instead of an eye as a means of attachment.

The object of the invention being to provide for a watch or other similar article an attaching device, for attachment of a bracelet, chain, or the like, which, when not in 80 use, can be closed into the case so as to be practically invisible, but can be extended readily when desired, it will be understood that such disappearing attaching device or devices can be applied at one or at a plurality of points. In Fig. 1 of the drawing is shown a bracelet watch *a*, having an ordinary bow *b* to which is attached one end of a bracelet *c*, the other end being attached to the watch, as at *d*, at a point diametrically 85 opposite the bow *b*, by means of a disappearing attaching device, which is extended to permit it to be used for the attachment of the bracelet. In Fig. 2 the same watch *a* is shown as having a chain *c'* attached to the 90 bow *b*, while the diametrically opposite attaching device, the location of which is indicated at *d* by the usual case hinge, is not itself visible, having been closed into the case. A watch which is adapted to be used 95 either as a bracelet watch, as shown in Fig. 1, or as a chain-sautoir watch, as shown in Fig. 2, is commonly known in the trade as a convertible watch.

Referring first to the embodiment of the 100 invention illustrated in Figs. 3, 4, 5 and 6, it will be seen that the center *e* of the watch, having hinged thereto on one side the back *e'*, and having applied thereto on the other side, in the usual manner, the bezel *e''*, is 105 110

provided, adjacent to the hinge e^3 , by which the back is connected to the center, with a horseshoe shaped seat e^4 , which extends through the hinge line. A horse-shoe shaped eye or disappearing attaching device is also hinged upon the same pintle e^5 of the hinge e^3 and is adapted to be turned down into the recess e^6 , as shown in Figs. 2, 3, 4 and 6, when it is practically invisible, or to be extended, as shown in Figs. 1 and 5, to serve as a means of attachment for a chain or bracelet. The eye or attaching device f may be provided with a small lug or projection f' , for convenience in engagement by the finger nail or by a suitable tool, or the seat e^4 may be cut away, as shown at e^8 in Fig. 6, to permit a pin point to be introduced below the edge of the eye to permit it to be raised out of the seat and extended as shown in Fig. 5.

It will be obvious that the eye or attaching device might be secured to the watch case in many different ways. Thus, in Figs. 7, 8 and 9, it is shown as secured to the watch case independently of the hinge and as swiveled. The eye f^2 is shown as hinged, as at f^8 , to a block f^2 which is swiveled in the watch case center e . The head f^4 is located in a recess f^6 formed in the watch case center e and is of less diameter than such recess, thereby leaving an annular space into which the eye may be shut or folded, when it is not desired for use, and therefore become practically invisible.

In Figs. 10 and 11 the watch case center e is shown as having a seat or opening e^7 , extending in a circumferential direction while the eye f^6 is hinged within the center, as at e^8 , so as to be closed into the case, as shown in Fig. 10, or to be extended, as shown in Fig. 11, having projections f^7 and f^8 which prevent excessive movement of the eye in either direction and close the slot when the eye is in either extreme position.

In Fig. 12 the watch case center is also shown as slotted in longitudinal direction, as at e^9 , while the eye f^6 , fitting friction-tight in such opening, is carried by a spring f^{10} , which is secured, by a rivet or solder, as at f^{11} , to the center, the eye being provided with a projection f^{12} for convenience in extending the eye, such projection serving also

to cover the end of the slot when the eye is closed in.

The attaching device need not necessarily have the form of an eye, as shown in the several embodiments already described, but it might be formed as a knob f^{13} , adapted to be engaged by a link f^{14} with a key-hole slot f^{15} , as shown in Fig. 13. Such knob or headed attaching device might be carried by a spring f^{16} and fit friction-tight in an opening in the watch case center, substantially as already described with respect to Fig. 12. 65

Many other possible embodiments of the invention, both with respect to the character of the attaching device and to the means for supporting it movably with respect to the watch case, so that it may be shut into the watch case and practically disappear or be extended when desired, will readily suggest themselves and the invention, therefore, is not restricted to any particular construction and arrangement shown and described herein. 70

I claim as my invention:—

1. The combination with a watch case, of an attaching device movably secured to the watch case and adapted to be extended for use or to be closed in so as to become practically invisible, the watch case having a seat to receive the attaching device when it is closed in. 80

2. The combination with a watch case, of an attaching device hinged on the watch case and adapted to be extended for use or to be closed in so as to become practically invisible, the watch case having a seat to receive the attaching device when it is closed in. 85

3. The combination with a watch case having a recess, of a swiveled head mounted in the recess and smaller than the recess so as to leave a space about it, and an eye hinged to the swiveled block and adapted to be closed into said recess so as to become practically invisible. 95

This specification signed and witnessed this 8th day of January, A. D., 1915.

CHARLES L. DEPOLLIER.
